CARRIER FOR OUTBOARD MOTORS

Milburn B. Cross, Chino, Calif.

Application November 29, 1948, Serial No. 62,505

3 Claims. (Cl. 206—46)

1

My invention relates generally to accessories for outboard motors, and more particularly to a carrier for such motors.

In spite of the widespread popularity achieved by outboard motors for boats, there has heretofore been no simple and rugged carrier for such motors that permits them to be easily and safely stowed in a car or airplane for carrying from one place to another. Many of the owners of such motors have provided canvas or similar covers to enclose and protect them from dust, dirt, and other foreign matter, but even when this is done there is no protection for the motor against external injury from adjacent objects. Racks or similar devices to support the motor in an upright position have been developed for displaying the motors in stores, etc., but it is obvious that a stand intended to display a motor so that all the parts of the latter are readily accessible, is considerably different from a carrier where the various elements of the motor are to be protected.

To secure the maximum protection, the motor must be held securely in the carrier, and the carrier itself must be held against violent movement. For example, many of the outboard motor enthusiasts own and operate their own airplanes, and in some sections of the country clubs have been formed whose members make regular trips in their planes, carrying their motors with them. On several occasions, because of the inadequate means of carrying the outboard motors within the light planes, the motor has come loose while the plane is in flight, jamming the controls, and requiring that the pilot and any passengers parachute to safety. While the problem is not so severe in the case of motors carried in automobiles, the need for protection still exists.

Consequently, it is a major object of my invention to provide an improved carrier for outboard motors.

Another object of my invention is to provide a carrier of this type that offers mechanical protection to the motor itself.

A further object of my invention is to provide a carrier in which the motor itself may be securely held, and the carrier in turn lashed or otherwise securely held in place.

Still another object of my invention is to provide a carrier having these features that also provides convenient means for grasping and moving the carrier and motor as a unit.

It is a still further object of my invention to provide a carrier with these characteristics that is adapted to receive and protect substantially

all of the different types of outboard motors now available, so that by the single purchase of one of my improved carriers, the owner thereof is provided with a carrier that will receive not only his present motor but any other motor he may purchase.

These and other objects and advantages of my invention will become apparent from the following description of preferred and modified forms thereof, and from the drawings illustrating those forms in which

Fig. 1 is a perspective view of my improved carrier as it appears prior to the placing of a motor therein;

Fig. 2 is a plan view of the carrier shown in Fig. 1;

Fig. 3 is a side elevational view, with an outboard motor indicated in phantom outline to show the method of carrying the latter;

Fig. 4 is a cross-sectional view taken on the line 4—4 of Fig. 2, showing the construction and attachment of the drive shaft retaining means;

Fig. 5 is a view taken on the line 5—5 of Fig. 4 to show the adjustable mounting of the cradle plates; and

Fig. 6 is a fragmentary detail view of an optional method of mounting the drive shaft retaining means, this method of construction being used where only motors of a certain predetermined size are to be carried.

Referring now to the drawings and particularly to Figs. 1 to 3 thereof, the numeral 10 designates generally a frame having a lower section 11 and an aligned but non-parallel upper section 12. The sections 11 and 12 have converging sides, and at their wider ends, the sections are held together by stanchions 13. At the opposite or narrower ends, the sections 11 and 12 are connected together by shorter stanchions 14, and thus the wider ends of the sections are spaced apart a greater distance than the narrow ends. Within this frame 10 I place the outboard motor 15, the power head, including the gas tank and other upper portions of the motor, being cradled in the wider portion of the framework, while the propeller and lower portions of the motor are located in the narrow section of the frame. As indicated in Fig. 3, when the motor 15 is laid in a horizontal position, the propeller does not extend so far upwardly as the power head, and consequently the frame adjacent the propeller need not be so high to secure adequate protection for it.

Turning now to a more detailed description of the carrier, the lower section 11 is preferably

formed of angle members or other suitable structural form, with an angle member 16 forming one side of the portion 11, and a similar member 17 forming the other side. As previously mentioned, the members 16 and 17 converge toward each other, and for reasons which will hereinafter become apparent, I prefer to place the angles so that their horizontal flanges or legs form the upper surface of the section 11, while the vertical legs are on the outside.

At the narrower end of the section 11, the angles 16 and 17 are joined together by an end member 20 that is formed of either straight or curved sections of angle or other suitable members. Though the load imposed upon this section of the lower portion 11 is not particularly high, the end member 20 acts as a very convenient handle for grasping the frame 10. At the wider end of the section 11, the angles 16 and 17 are connected together by a cross-piece 21, preferably of a flat or strip-like material.

I thus form a rigid, light-weight sub-frame or section 11 which is further braced by a bed plate 22 extending between the side angles 16 and 17 near the end 20. As indicated in Figs. 1 and 2, the bed plate 22 extends along the sides 16 and 17 for an appreciable distance, and is securely fastened to these members as by welding, riveting, or other suitable means to brace the sub-frame 11 and act in the general manner of a diagonal brace. The central section of the bed plate 22 is provided with a number of pairs of holes 23 spaced on each side of the axis of the frame 10, and adapted to receive drive shaft retaining members 24, hereinafter described.

The previously mentioned stanchions 13 at the wider end of the frame 10 are preferably attached to the cross-piece 21 at the ends thereof, and project upwardly to the upper portion 12 where they are attached by welding or other suitable methods. The section 12, like the section 11, is preferably formed of suitable structural forms such as angles, and has side members 16a and 17a, comparable to the similar sides of the lower section 11. Like the last-mentioned sides, the sides 16a and 17a converge and are joined at their closer ends by an end section 20a that may be formed of curved or straight sections of angle members. The previously mentioned stanchions 14 are firmly anchored to the sides 16, 16a, 17 and 17a to support the upper section 12 and maintain it in the proper position with respect to the lower section 11.

At the opposite ends of the upper section 12, the sides 16a and 17a are connected by a protective end member 25 that, like the ends 20 and 20a, may be formed of straight or curved sections of angle or other structural members. However, because of the shape of the motor 15 that is carried in the frame 10, the sides 16a and 17a are longer than the corresponding sides 16 and 17 of the lower section 11, and the end 25 is thus located beyond the end of the lower section 11 to encircle the power head of the motor.

It will be appreciated that the frame 10 is of a size sufficient to receive a conventional outboard motor 15, without being so much larger than the motor as to be wasteful of space. The frame 10 also acts in the same general manner as a crate to protect the motor from external injury, and locating and aligning members are mounted in the frame to hold the motor against movement therein. As previously indicated, the bed plate 22 is provided with drive shaft retaining members 24 that engage the sides of the shaft and hold it against lateral movement. Prefer-

ably, the members 24 are formed of V-shaped rod-like members with downwardly divergent legs, the legs of both members preferably lying in a single plane which is perpendicular to the longitudinal axis of the frame 10.

As indicated in Fig. 4, the adjacent legs of the members 24 are preferably perpendicular to the bed plate 22, while the outer or remote legs are at an angle to the adjacent legs and diverge downwardly to the edges of a base plate 26. The members 24 are preferably welded or otherwise securely held to the base plate 26, and the parallel, adjacent legs extend through the base plate to pass through the holes 23 of the bed plate, being held therein by wing nuts 27 or other suitable holding means. In this manner, the members 24 are securely held to the base plate 26 and to the bed plate 22, while remaining readily adjustable along the axis of the frame 10 to take motors 15 having propeller shafts of different length.

At the opposite or larger end of the frame 10, I provide means to cradle or support the power head, including the gasoline tank and other associated portions of the motor 15. As best seen in Figs. 2 and 5, this cradle support includes a pair of downwardly convergent plates 30 mounted on angularly positioned rods 31 and adjustable along the latter to vary the separation of the plates. The lower ends of the rods 31 are attached to the cross-piece 21 at points located inwardly from the stanchions 13, while the upper ends of the rods are connected to the upper end of the stanchions. In this manner, the angularly positioned rods 31 act to brace and stiffen the stanchions 13 and the frame 10, thereby adding rigidity to the entire structure.

The plates 30 are preferably curved to conform with the shape of the portions of the motor received therein, and also to hold the motor against longitudinal movement within the frame 10. Since motors have power heads of different sizes and shapes, the plates 30 must be adjustable if a truly universal carrier is to be provided. In my present design, I have solved this problem by providing the plates 30 with outwardly projecting ears 32 that are held to the rods 31 by means of screws 33. Preferably, the screws 33 clamp the ears 32 to the rods 31 so that the plates 30 may be held in any desired position along the length of the rods. By reason of the angular positioning of the rods 31, the plates 30 are separated as they are moved upwardly, away from the cross-piece 21, and are moved toward each other as they are moved toward the cross-piece. Consequently, a small motor 15 may be held within the frame 10 just as securely as a larger motor.

To complete the carrier and to insure the firm holding of the motor 15 within the carrier, I provide straps 34 and 35 riveted or otherwise securely held to the side members 16 and 17 of the lower section 11, and provided with a buckle 36 or other form of engaging means to hold the motor firmly in place.

In using my improved carrier, the plates 30 are first positioned in the approximate location where they will properly receive and support the power head of the motor 15. The base plate 26 and the drive shaft retaining members 24 are placed so that these members will engage the drive shaft of the motor 15 at the proper location. The nuts 27 are then tightened, and the motor 15 is placed within the carrier 10. At this time, final adjustment of the position of the plates 30 is made so that the gasoline tank and operating portions

of the motor 15 are firmly supported and held against downward movement and also against end movement. Thereafter, the bolts 33 are tightened to retain this adjustment, and the straps 34 and 35 are passed over the motor and connected together so that the motor is held against upward movement with respect to the frame 10. It is then a simple matter to carry the entire assembly of frame and motor by grasping the end pieces 20a and 25, and the frame may easily be slid along the floor of a luggage compartment of a car by reason of the runner-like effect of the angle members 16 and 17. The frame 10 may easily be lashed to suitable members of an airplane or automobile to prevent any movement of the frame, and the motor 15 is firmly held within the frame against any movement with respect thereto.

It will be appreciated that by reason of the construction herein employed, a very lightweight but sturdy carrier is provided. While a heavier carrier may very easily be constructed, the present form affords ample protection for the motor 15, and its light weight renders it just that much easier to handle. In this regard, it will be appreciated that the light weight of my carrier renders it particularly suitable for use in aircraft, and while the various structural members going to make up the complete frame 10 may be formed of steel or iron, I have found that in general, sufficient rigidity and strength is provided if the members are formed of a lightweight aluminum alloy.

Where the lightest possible weight is desired and the adjustability of my preferred form is not essential, I may use the optional form indicated in Fig. 6. In this form, the upper and lower sections 11 and 12 are formed as previously indicated, and are joined by stanchions 13 and 14 as in the preferred form. However, the bed plate 22 is omitted, and instead the base plate 26 is welded or otherwise securely attached directly to the side members 16 and 17. The adjacent parallel legs of the drive shaft retaining means 24 are welded or otherwise securely held to the base plate 26a, instead of passing through the latter and the bed plate 22. While this form does not have the adaptability of my preferred form, since it is not intended to receive motors having drive shafts of greatly different lengths, it nevertheless is a very sturdy and efficient carrier. In all other ways, it is used in the identical manner as the preferred form, and it will be appreciated that in each of these forms, once the initial adjustment of the retaining means 24 and the plates 30 has been accomplished, the motor may thereafter be placed in and removed from the carrier by simply connecting or disconnecting the straps 34 and 35.

It will thus be seen that I have provided an improved carrier for outboard motors that is simple, rugged, and dependable, while providing the maximum necessary protection for the motor. It will be appreciated that such a carrier may be formed from many different suitable structural forms in addition to the angle members mentioned, among such forms being rods, tubes, and channels. However, in each case the fundamental principles of construction remain the same and are clearly within the scope of the invention defined herein. Consequently, I do not wish to be restricted to the particular form or arrangement of parts herein described and shown, except as limited by my claims.

I claim:

1. A carrier for outboard motors which includes: a lower frame having convergent sides; an upper frame generally aligned with said lower frame and having converging sides; members connecting said upper frame to said lower frame to hold the wider ends of said frames farther apart than the narrow ends thereof; upwardly divergent members extending between said upper and lower frames at one end thereof; adjustable cradle members mounted on said divergent members to receive and hold the upper end of said motor against movement with respect to said frames and in a position wherein the major portion of said motor is between said upper and lower frames; and bifurcated retaining means movably mounted between said upper and lower frames for adjustment along the longitudinal axis thereof, to receive the propeller end of said motor and hold it against lateral movement with respect to said frames.
2. A carrier for outboard motors which includes: a lower frame having converging side members, an end member at the narrow end of said frame joining said side members, and a cross-piece extending between said side member at the wider end of said frame; an upper frame having converging side members, an end member at the narrow end of said frame to connect said side members, and a larger end piece at the wider end of said frame, extending between said side members; stanchions connecting said upper and lower frames together, the stanchions at the wider ends of said frames being taller than those at the narrow ends of said frames so that said frames converge toward their narrow ends; upwardly divergent rod-like members extending from said cross-piece to the upper ends of said longer stanchions; cradle members adjustably mounted on said rod-like members for movement along the axes of the latter, said cradle members being curved to receive and hold the upper end of a motor against movement with respect to said frames, said motor when so held having its major portion between said frames and protected thereby; a bed plate rigidly connected between said side members of said lower frame and having a number of pairs of holes therein along the longitudinal axis of said frame, the holes of each of said pairs of holes being laterally aligned and on opposite sides of said axis; a base plate for mounting on said bed plate; and spaced retaining members mounted on said base plate and held thereto, the ends of said retaining members being positioned to extend through a pair of said holes in said bed plate, and said members adapted to receive the propeller end of said motor to hold the latter against displacement with respect to said frames.
3. A carrier for outboard motors which includes: a lower frame having converging side members, an end member at the narrow end of said frame joining said side members, and a cross-piece extending between said side members at the wider end of said frame; an upper frame having converging side members, an end member at the narrow end of said frame to connect said side members, and a larger end piece at the wider end of said frame, extending between said side members; stanchions connecting said upper and lower frames together, the stanchions at the wider ends of said frames being taller than those at the narrow ends of said frames so that said frames converge toward their narrow ends; upwardly divergent rod-like members extending from said

cross-piece to the upper ends of said longer stanchions; cradle members adjustably mounted on said rod-like members for movement along the axes of the latter, said cradle members being curved to receive and hold the upper end of a motor against movement with respect to said frames, said motor when so held having its major portion between said frames and protected thereby; a base plate rigidly connected between said side members of said lower frame near the narrow end of said frame; and spaced retaining members mounted on said base plate to receive the propeller end of said motor and hold the latter against displacement with respect to said frame.
